REFRIGERATED FAN GUARD

Nellie G. Keller and William J. Keller,
St. Louis, Mo.

Application July 30, 1946, Serial No. 687,084

1 Claim. (Cl. 257—259)

1

This invention relates to electric fan guards, and, more particularly to a refrigerated fan guard.

An object of the invention is to provide a refrigerated fan guard embodying an evaporator of a type wherein a continuous circulation, in a sinuous path, can be maintained by using a liquid refrigerant.

A further object of the invention is to provide an electric fan guard with an evaporator in which heat from a continuous passing flow of air therefore is chilled as it passes over and around the evaporator so that the temperature of the air delivered by the fan blades will be reduced over the customary method of cooling with a fan without an evaporator forming a part of the guard structure.

According to the present invention, the evaporator is an independent unit supported by a skeleton wire fan guard providing thereby a circulatory system in a fan created air flow and within the bounds of the outside diameter of the fan guard.

A further object of the invention is to provide an evaporator unit formed of tubing and designed to include a plurality of spaced sections, varying in length, connected by end bends, and having a general circular formation in front elevation.

A further object of the invention is to provide a fan blade guard for electric fans with an evaporator, or cooling unit in which a liquified refrigerant is permitted to vaporize, and which can be connected with either an absorption refrigeration apparatus, or a refrigerating unit employing a compressor, so that the flow of air currents delivered by the fan blades will be chilled.

A further object of the invention is to provide an arrangement of a fan blade guard for electric fans and an evaporator, or cooling unit, wherein a refrigerant is permitted to vaporize, and where the expansion of the refrigerant vapor absorbs heat from passing air to reduce the temperature of air currents delivered by the fan blades.

With the above objects in view, together with such other objects and advantages as may subsequently appear, the invention resides in the parts, and in the combination, construction and arrangement of the parts hereinafter described and claimed, and illustrated by way of example in the accompanying drawings, in which:

Fig. 1 is a front elevation of a fan guard embodying the features of the invention.

2

Fig. 2 is a sectional view taken on line 2—2 of Fig. 1.

Fig. 3 is a rear elevation of the fan guard.

Fig. 4 is a side elevation of the fan guard.

Referring to the drawings, the fan blade guard consists of a skeleton wire guard structure designated, generally as A, and an evaporator designated, generally as B.

The skeleton wire structure A in the embodiment shown, comprises a plurality of spaced concentrically arranged front wire rings 1, 2 and 3, a plurality of spaced concentrically arranged rear wire rings 4, 5 and 6, which are spaced a suitable distance to the rear of the rings 1, 2 and 3. A plurality of wire members including a straight front section 7 having a curved outer end section 8, serve as connecting braces between the front rings 1, 2 and 3 and the rear outer ring 6. The rings 1, 2 and 3 are suitably secured to the section 7 and the ring 6 is suitably secured to the free end of the curved section 8 by means such, for instance, as solder, or spot welding. A suitable wire ring 9, which forms the outer diameter of the skeleton guard, connects the curved sections 8 at the highest points thereof, and the ring 9 is secured to the curved sections 8 by means such, for instance, as solder, or spot welding to further reinforce and strengthen the skeleton guard structure. A plurality of suitable V-shaped wire members 10 having a loop, or fastener receiving eye 11 are secured to the rear rings 4, 5 and 6. The members 10 are suitably secured to the rear rings 4, 5 and 6 by means such, for instance, as solder, or spot welding.

The members 10 are adapted to be secured to an electric fan motor 12 by means of suitable fasteners 13 to support the skeleton guard in position relative to the motor and to the fan blades 14 which are housed within the guard structure 40 and driven by the motor for delivering a continuous flow of air away from the motor.

The evaporator designated, generally as B comprises a single tube, pipe, or conduit, and, in the embodiment shown, includes a plurality of suitably spaced straight horizontal sections or runs 15 of various lengths on opposite sides of the horizontal center line of the evaporator. The sections 15 are connected at their ends by curved bends 16, the outer ends of which are confined within the bounds of the outside diameter of the skeleton guard A so that the evaporator will appear as of round or circular outline in front and rear elevation. One of the end sections of the evaporator is preferably bent, as at 17, providing thereby a rearwardly projecting section 18

for connection with a suitable refrigeration apparatus, not shown, and the other end section of the evaporator is bent, as at 19, providing thereby a rearwardly projecting section 20 for connection with the refrigeration apparatus. The refrigerant employed is introduced into one end, or the other of the evaporator from the refrigeration apparatus and permitted to vaporize in the sinuous circulatory path through the evaporator where the expansion of the refrigerant vapor will absorb heat from passing air delivered by the fan blades and thereby chill, cool, or in other words reduce the temperature of the air delivered past the evaporator by means of the fan blades. The evaporator is shown as dished due to curved bend portions being curved rearwardly, as at 21.

From the foregoing description, it will be apparent refrigerated air will pass from the evaporator and be carried therefrom into the room in front of the fan.

The many advantages of the herein described invention will be apparent to those skilled in the art to which it appertains.

What we claim is:

An evaporator coil adapted to be mounted upon

5 and fixed to the front face of an electric fan guard, said coil comprising a single length of tubing formed to provide spaced straight horizontal runs of various lengths on opposite sides of the horizontal centerline of the evaporator, said runs connected at their ends by curved bends, and the horizontal runs adjacent the curved bends being curved rearwardly to arrange the curved bends to lie in a circular outline to the rear of the spaced straight horizontal runs.
